UNITED STATES PATENT OFFICE.

WALTER F. ROLSTON, OF ROCKFORD, ILLINOIS, ASSIGNOR OF ONE-HALF TO WILLIAM H. ZICK, OF ROCKFORD, ILLINOIS.

YARN-CHANGING MECHANISM.

Application filed December 21, 1923. Serial No. 681,989.

This invention relates to straight knitting machines, and has more particular reference to yarn-changing mechanism therefor, of the type disclosed in United States Letters 5 Patent No. 616,601, to William Worth Burson, and to control mechanism therefor, of the type disclosed in United States Letters Patent No. 944,012, to Wilson W. Burson; and the present invention is an improvement 10 on such type of mechanism.

One of the primary objects of my invention is to reduce friction and wear of the operating parts, and to increase the life and promote greater accuracy in the operation of such parts; and further, to lower 15 the cost of maintenance of this type of knitting machine in so far as the mechanism is concerned.

I have also aimed to provide a novel 20 yarn-changing mechanism, whereby a greater number of yarn changes may be made, thus enabling greater variety in the design and make-up of knitted goods produced on straight-knitting machines.

25 The manner in which these objects are accomplished will be readily understood by those skilled in this art by reference to the following description and drawings.

Likewise, other objects and attendant 30 advantages will be appreciated as the invention becomes better understood by reference to said description and drawings, in which—

Figure 1 is an end elevation looking at the transfer end of a straight-knitting machine embodying my invention;

Fig. 2 is a side elevation of the machine, with certain parts broken away, in section, and others removed, with the view to showing only such parts as are necessary for an 40 understanding of the present invention;

Fig. 3 is an enlarged side view partly in section, of the transfer control mechanism shown in Fig. 2; the parts in section being substantially on the line 3—3 of Fig. 4;

Fig. 4 is a plan view of the parts shown in Fig. 3;

Fig. 5 is a fragmentary sectional view taken substantially on the line 5—5 of Fig. 4;

50 Figs. 6 and 7 are fragmentary views showing different operated positions of the transfer control switch, looking at the side opposite from that shown in Fig. 3;

Figs. 8 and 9 are detail sections taken on 55 the lines 8—8 and 9—9 of Fig. 6;

Fig. 10 is a fragmentary vertical section taken substantially on the line 10—10 of Fig. 3;

Fig. 11 is a fragmentary view of the yarn-changing device as shown from the section 11—11 in Fig. 2;

Fig. 12 is a section through the yarn-changing device taken on the line 12—12 of Fig. 11; and

Fig. 13 is a diagram of a stocking, illustrating one example of yarn changing with mechanism embodying my invention.

The knitting machine shown in the drawings to which my invention has been applied for purpose of illustration merely, is known 70 in this art as a Burson straight-knitting machine. These machines knit either flat or tubular fabric, and are especially adapted for producing fashioned articles such as stockings, by bringing a greater or less 75 number of needles into action; and different yarns are brought into action from time to time by means of the yarn-changing mechanism to vary the character of the knitting as to material, weight, color, etc. Inasmuch as the present invention relates primarily to the yarn-changing or transfer mechanism, only so much of the machine is shown in the above-mentioned drawings as is necessary for an understanding of the invention.

The parts well known to this art comprise a base or standard 15 and a frame 16 which carries opposed beds in turn supporting banks of needles, not shown, but which are 95 adapted to be advanced and retracted in the knitting action by cam bar slides 17. The cam slides are adapted to be reciprocated by a cross-head 18, Fig. 2, which in turn may be reciprocated by any suitable mechanism, 100 that shown, comprising a lever 19 connected by means of a rod 21 to an endless chain 22 trained over driving and idler sprocket wheels 23, the parallel upper and lower reaches of the chains imparting uniform 105 movement to the cross-head during the forward and return strokes. This particular driving mechanism is, however, a departure from the usual construction and constitutes the subject matter of a co-pending application. The sprocket wheel 23 is at present driven by means of a gear 24 meshing with a large spur gear 25, the latter of which is 110 part of the yarn-changing mechanism, the numeral 25 also denoting the gear body or 115

wheel which carries part of said mechanism, which will be presently described.

The gear 25 is adapted to be continuously driven when the machine is in operation by a spur pinion 26 fixed to an initial drive shaft 27, in turn adapted to be driven by any suitable means, such for example as by a belt. Said gear 25 is fixed to a drive shaft 28 journaled on the frame in bearings 29 and 31 on the frame and carries a mutilated worm 32 which intermittently revolves a worm gear 33 connected by an intermediate spur pinion with a gear 34 on one of the pattern cylinders 35. Said gear 34 meshes with a corresponding gear 36 on the other pattern cylinder 37. As is well known in this art, one of the functions of the pattern cylinders is to control the number of needles in action, and consequently the shape of the fabric. The mechanism just described for driving the pattern cylinders is disclosed in Patent No. 616,601, above mentioned.

Said patent also discloses the use of one or more yarn-carriers which traverse the needle beds in timed relation with the needle action for feeding the yarn to the needles, the yarn-carrier in operation being supported (except when in the yarn-changing device) on stationary ways 30 above the needles and being reciprocated by a bar 38, Fig. 2, connected to the cross-head 18 above mentioned. My invention contemplates the use of similar yarn-carriers, and likewise a yarn-changing or transfer mechanism at the "home end" of the yarn-carrier movement, as disclosed in said patent.

However, the present invention provides an improved yarn-changing mechanism both as regards the shiftable device for moving the yarn-carriers into and out of registration with the reciprocating bar 38 and the mechanism for shifting said device. The yarn-changing device will first be described.

Referring more particularly to Figs. 1, 2, 11 and 12, it will be observed that I have provided a yarn-changing or transfer carriage designated generally by 39, which is arcuate or segmental in shape as distinguished from either circular or flat as previously known to this art. The transfer carriage may be supported by suitable means to shift back and forth in the arcuate plane in which it is disposed. At present I have mounted the carriage on a supporting part 41 fixed to the frame of the machine and having a segmental guide 42 T-shape in cross-section, fitting in complementary ways in the carriage 39. Said carriage has spaced throughout its length, a plurality, five in the present instance, of sets of ways 43 each for the reception of a yarn-carrier 44. The ways 43 holding a yarn-carrier on the vertical center line of the machine, are in registration with stationary ways above the needles, so that each time a yarn-carrier

is brought to the home end of its stroke by the bar 38, it will leave said stationary ways and enter onto the ways 43. The bar 38 has a head 45 as shown in Fig. 2, with opposed abutments 46 and 47 for actuating the interposed upturned end 48 of a yarn-carrier. By reason of the space between the abutments 46 and 47, there will be an interval at the end of the stroke during which the carriage 39 may be shifted in either direction to position the next succeeding yarn-carrier in registration with the stationary yarn-carrier ways and to bring its upturned end or lug 48 between the abutments 46 and 47, so that when the bar 38 moves away from the transfer mechanism in its next stroke, the yarn-carrier thus positioned will be carried off its ways 43 and onto the stationary ways, into action. It will thus be apparent that by shifting the carriage 39 in a quick movement at the proper time, the yarn-carrier in the working position or station will be removed therefrom and another substituted in its place, and that by successive movements of the carriage each yarn-carrier may in turn be brought to said station and into operation.

Some of the advantages of this construction are that a greater number of yarn-carriers can be accommodated in a limited space, and that the yarns from the idle yarn-carriers are held in such angular relation as not to cross or interfere one with another. With the circular type of yarn-changer only a limited number of yarn-carriers may be used without interference of yarn; and with the flat type the end yarn-carriers are carried a considerable distance from the working position, which is objectionable also because of yarn interference and to the length and angle of the yarns.

The mechanism for shifting the yarn changing or transfer carriage, will now be described. In the present embodiment of my invention, said carriage is shifted by mechanism operated by rotative movement of the gear or wheel 25. The operation of this mechanism is in turn controlled by suitable means, such as one or more transfer plates embodied in what is known in this art as a controller cylinder designated generally by 49. The operation of a controller cylinder of this type is disclosed in Patent No. 990,595, above mentioned; but such mechanism operable between such controller cylinder and the yarn-changing device is objectionable for reasons which will be presently pointed out. My present invention, provides an improved mechanism for operating a yarn-changing device at predetermined intervals, which will now be described.

As shown in Figs. 1, 2 and 11, the transfer carriage 39 has a rack 51 with which meshes

a spur gear 52 fixed to a shaft 53 which is suitably journaled on the frame and equipped at its opposite end with a spur pinion 54 meshing with the rack face on an upright bar 55. This bar, suitably guided at its upper end in a bearing bracket 56 and at its lower end in a bearing bracket 57, is adapted to be moved vertically by rotative movement from the wheel 25 for translating movement to the yarn-changing or transfer carriage 39 through the agency of the gearing connection between said bar and carriage. Suitable means is provided such as a spring pressed plunger 58 in the bracket 56, for imposing friction on the bar 55, tending to reduce vibration and inertia thereof.

The translating bar 55 is equipped at its lower end with a series of rollers 59 which 20 may correspond in number with the sets of ways 43 on the transfer carriage, although in the present instance I employ one roller less than there are positions or ways for yarn-carriers and utilize a stop on the bar 25 for determining the other position. Any one of these rollers is adapted to ride on the periphery of an annular track 61 fixed to the wheel 25, whereby the bar 55 and connected parts are held in a position determined by 30 the particular roller on the track. As best shown in Fig. 3, a portion of the track is pivotal, providing what I term a switch 62, pivoted at 63. Mechanism is provided as will be presently described, for shifting 35 this switch in a clockwise direction viewing Fig. 3, to provide a gap in the track and position its face 64 beyond the outer face of said track and in the path of the roller thereabove, so that when the wheel 25 is 40 revolved in a counter-clockwise direction viewing said figure, the switch face 64 will engage said roller and move it down through said gap to the underside of the track, thereby shifting the bar 55 downwardly a distance sufficient for moving the transfer carriage one position to the left, viewing Fig. 45 11. And when said switch is shifted in the opposite direction to present its outer face 65 beneath or within the internal face 66 of the track and in the path of the roller positioned just beneath or at the inner side of said face 66, said roller will be engaged by the switch face 65 at the proper time in the rotation of the wheel 25 and carried by 50 said face to the outer track face 61, thereby elevating the bar 55 one position and correspondingly shifting the transfer carriage one position to the right, viewing Fig. 11. Thus, it will be seen that with the switch in the 55 full line position shown in Fig. 3, the wheel 25 may be continuously revolved without disturbing the transfer carriage, and that upon shifting the switch 62 in either direction, the transfer carriage will be correspondingly shifted one position upon each

revolution of the wheel. The bar 55 may be shifted successively in either direction, its elevation being limited in opposite directions by stops 60 and 67, the former of which by contact with the underside of the bearing bracket 57 limits the raising movement of said bar, and the latter, by contact with the top of said bracket limits the lowering movement. The latter contact is made when the uppermost roller is disposed beneath the track surface 66. The stop 67, therefore, is determinative as is each of the rollers, of one position of the yarn-changing device.

The position of the switch 62 is controlled by mechanism which will be presently described, so that shifting of the bar 55 is positively determined and is never beyond the upper or lower limit mentioned. Suitable means is provided for holding the switch in any of its operated positions, comprising in the present instance, means for imposing friction between the switch and the wheel 25. Referring to Fig. 9, this is done by a spring 68 carried by a pin 69 fixed to the switch 62 and disposed in an arcuate slot 71 in the wheel, the function being obvious.

The means for shifting the switch, best shown in Figs. 3, 6 and 7, comprises a shiftable cam 72 pivoted at 73 on a stationary bracket 74 which carries the bearing portion 57 above mentioned, in conjunction with a stationary cam throat designated generally by 75, formed integral with the bracket 74. Said pivoted and stationary cam parts 72 and 75 respectively, are located in the path of a laterally projecting lug or pin 76 on the switch 62, for the purpose of actuating said pin, and in close proximity to the bar 55 for actuating said pin and consequently shifting the switch just before the latter reaches the bar. The shiftable cam 72 has an accurate groove 77 intersecting the plane of its pivot pin 73; and this pivot pin 73 as well as the pivot 63 of the switch are located the same radial distance from the shaft 28. The cam groove 77 being struck on an arc of the same radius and the switch pin 76 being on said radius when in the normal position shown in Fig. 3, it will ride idly through the cam groove 77 during continued rotation of the wheel 25 until the position of the cam 72 is changed. The cam throat 75 has a relatively wide mouth defined by opposed surfaces 78 and 79 which converge to a narrow opening 81 in registration with the cam groove 77 in its normal position. By lowering the outer end of the cam 72 to the position shown in Fig. 7, its top surface 82 will be brought into registration with the opening 81, so that the next time the switch pin 76 comes around it will ride on said surface 82 and be raised thereby to bring the switch face 64 into action for lowering the bar 55 one position

as described above. Upon shifting the cam 72 in the opposite direction for bringing its surface 83 into registration with the opening 81, the switch pin 76 will be actuated 5 by said surface 83, causing the switch surface 65 to be brought into action for raising the translating bar 55 one position. After each actuation of the switch 62 in this manner, its pin 76 will upon being carried 10 around to the stationary cam throat 75, strike either the cam face 78 or 79 as the case may be, and be returned thereby to the neutral position defined by the cam groove 81 in the desired operative relation to the 15 shiftable cam 72. Thus, the resistance to returning the switch to its neutral position is absorbed by the stationary throat cam. The resistance to shifting the switch is also absorbed by stationary parts in the form of 20 stops 84 and 85 fixed to the bracket 74, which stops provide stationary support for the shiftable cam 72. It will be apparent that in either shifted position of the cam, it is supported at opposite ends (so far as 25 resistance to shifting the switch is concerned) by its pivot pin 73 and either one of the stops 84 or 85. As a consequence of the foregoing construction, the shock from shifting the switch and likewise the translating bar 55 is in no way felt in the mechanism beyond the shiftable cam 72. This is 30 of importance, since in prior constructions this shock was carried through the switch-operating mechanism back to the transfer 35 or control plate, thereby causing excessive wear on these parts, especially the joints. As a result, prior constructions were comparatively short lived and also caused undue wear on the transfer plates to such an extent as to impair accuracy of control. The 40 present construction overcomes these objections, as will be apparent.

The mechanism for shifting the switch operating cam 72 will now be described, reference being had more particularly to Figs. 3, 4, 5 and 10. It is desired to shift the cam 72 to either the neutral, up or down position and to hold it in either of said positions during one or more courses of knitting. 45 This is done by one or more cam plates, better known in the art as transfer plates, on the controller cylinder 49, and means operated by a transfer plate for causing the cam 72 to be shifted. It will be observed, Fig. 50 10, that the transfer plate 86 has high, low, and intermediate faces 87, 88 and 89, respectively, cut in its periphery, and that a lever 91, which rides on said faces, is adapted to be moved thereby for in turn moving a train 55 of connections for translating the lever movement to the cam 72. In practice, there may be a series of levers 91 operated respectively by different transfer plates at different intervals for shifting said cam 72. At present, 60 four levers 91 are shown, pivotally mounted 65

on a rod 92 reaching across the top of the control cylinder. A cross-head 93 resting on top of the levers 91 and pivotally mounted on a rod 94 parallel with the rod 92, has a lug 95 disposed beneath a complementary lug 76 or finger 96 fixed to a rock shaft 97, which in turn is connected by means of a link 98 to the cam 72. The connection between said link 98 and the cam is at present through the agency of a member 99 parallel with and positioned on the side of the bracket 74 opposite from said cam and connected at one end to the pivot pin 73 of the cam and at its opposite end to a pin 101 reaching through an arcuate opening in said bracket 80 and being fixed to the cam. A contractile spring 102 connected between a fixed point and the member 99 tends to urge the cam operating connection in a direction to hold the cross-head 93 down against the levers 91, 85 and to return said levers, and likewise the cam 72, to the lowermost position. It will be manifest that by rotative step-by-step movement of the transfer plate 86 in a counter-clockwise direction viewing Fig. 10, 90 the lever 91 will be lowered to the surface 88, then raised successively to the surfaces 89 and 87, and then lowered, etc., according to the shape of the transfer plate, thus correspondingly shifting the cam 72 and 95 shifting the transfer carriage for the purpose of changing yarn-carriers as already described.

The transfer plate or plates as the case may be, will be operated to change yarn-carriers at predetermined times and in timed relation with the knitting operation, at present by means of ratchet or counting plates 100, as explained in said Patent No. 990,595. One or more pawls 103 are employed for imparting step-by-step movement to the counting plates, the pawls being reciprocated by means of a lever 104 from a cam 105 on the drive shaft 28. Thus, the transfer plates forming part of the controller cylinder are operated in timed relation with the pattern cylinders.

From the foregoing, it will be manifest that there are as many rollers or the equivalent on the translating bar 55 as sets of 115 ways on the transfer carriage or positions thereof, that there is but a single part and switch for guiding and shifting the rollers and consequently the transfer carriage, that the means for shifting the switch includes 120 a stationary and a movable cam element, that the switch-shifting means is so constructed as to absorb the resistance to the shifting of the switch and of the translating bar, and that there is no back pressure or 125 motion translated from the switch shifting means, or from the switch or parts operated thereby to the transfer plates, or means which control the operation of these parts. Consequently, these parts are subjected to 130

only ordinary wear, and in view of their construction are very durable and relatively long lived; and this construction insures greater accuracy and precision in shifting the yarn-changing carriage. Furthermore, this construction enables the practical use of a larger number of yarn-carriers than is possible with prior constructions of this general type, especially such as that disclosed in Patent No. 616,601, in which there are as many grooves or tracks in the face of the wheel corresponding to the wheel 25 in the present case, as it is desired to have movements in the transfer device, and in which the angle of the respective switches becomes more acute as they approach the center so that the action is not uniform for all switches and the number of switches is limited. In order to permit selective and quick shifting of the transfer carriage when setting up or testing the machine, or for any other reason, there is formed in the track an opening 114 (Fig. 3) diametrically opposite from the switch. This opening permits the rollers to pass through the track only when the latter is at rest.

As a further illustration of the advantages of my invention, I will explain the manner in which the four different yarns are used in knitting a fashioned, seamless stocking, reference being had more particularly to Figs. 11 and 13. The yarn-carriers employed in this operation are designated by numbers 1, 2, 3 and 4, respectively, these being held in the transfer carriage in the order shown. It is necessary to have one blank space on the transfer carriage in order to permit of reciprocation of the bar 38 without a yarn-carrier. Assuming that the No. 1 yarn-carrier is at the working station (which is occupied in Fig. 11 by the No. 2 yarn-carrier) this will be put into operation for knitting the toe from the point 106 to 107. The yarn carried by the No. 1 yarn-carrier is usually of a heavy grade and more durable than that used for the upper portion of the stocking. In knitting the top and bottom of the foot portion between the points 107 and 108, the No. 1 and No. 2 yarn-carriers will be used alternately as is well understood in this art. The No. 2 yarn, that is, the yarn carried by the No. 2 yarn-carrier is of a different grade or quality from the No. 1 yarn, and in the knitting of a silk stocking, would be the silk used for the upper portion. The heel will next be knit with the No. 1 yarn between the points 109 and 111. Following this, the No. 3 yarn-carrier will be brought into action alternately with the No. 2 yarn-carrier for knitting the portion of the stocking known as the high splice up to the point 112. The No. 3 yarn is approximately of the same weight as the No. 1 yarn, but has an admixture of silk so as to modify in appear-

ance that portion of the stocking showing above a low shoe and yet give the desired wearing quality at this point. The major portion of the stocking is then knit with the No. 2 yarn, in this instance the stocking being fashioned in the knitting without a seam. This knitting is carried to any suitable length, as for example to the point 113, when the No. 4 yarn-carrier is brought into action. This yarn-carrier is generally for cotton yarn and knits what is known as a garter or boot top, which likewise may be widened or fashioned in the knitting. It is customary to finish the stocking by one round of the No. 3 yarn, one of the No. 2 and one of the No. 1 yarns. Finally the blank position of the transfer carriage is shifted to the working station in order to permit the stocking to be shed from the needles. The yarn changes in this particular example are all controlled by one or more transfer plates and obviously innumerable variations are afforded by a transfer control of this kind, in conjunction with a transfer mechanism adapted for handling at least three or more yarn carriers.

It is believed that the foregoing conveys a clear understanding of the objects prefaced above; and while I have illustrated but a single working embodiment, it should be understood that equivalent parts and devices might be employed and many changes be made in the construction and arrangement without departing from the spirit and scope of the invention as expressed in the appended claims, in which—

I claim:

1. In a straight knitting machine, in combination, a yarn-changing device having a plurality of yarn-carriers, and mechanism for operating said device to move any yarn-carrier into an operative position, including a rotary member having a single track and a shiftable switch therein, and means for translating movement to said device for changing the position of the yarn-carriers, said means having a series of rollers indicative of the different yarn-carriers and adapted to be respectively brought into position on the track for determining the operative position of its respective yarn-carriers, said switch being shiftable to provide a gap in the track for roller passage when changing the position of the yarn-carriers.

2. In a straight knitting machine, in combination, a yarn-changing device having a plurality of yarn-carriers, and mechanism for operating said device to move any yarn-carrier into an operative position, including a rotary member having a single track and a shiftable switch therein, and means for translating movement to said device for changing the position of the yarn-carriers, said means having a series of rollers indicative of the different yarn-carriers and

adapted to be respectively brought into position on the track for determining the operative position of its respective yarn-carriers, said switch being shiftable to provide a gap in the track for roller passage, and said switch being operable to shift said roller-carrying means in either direction for changing the position of the yarn-carriers.

3. In a straight knitting machine, in combination with the stationary yarn-carrier ways, of a yarn-changing device comprising a segmental transfer carriage having four or more sets of yarn-carrier ways located side by side in an arc of relatively large radius and adapted to be shifted back and forth in said arc to move the respective sets of ways into and out of registration with said stationary ways, a gear segment on said carriage concentric with the center about which it is movable, a gear meshing with said gear segment, and means for imparting rotative movement to said gear for moving the transfer carriage back and forth.

4. In a stationary knitting machine, in combination with the stationary yarn-carrier ways, of a yarn-changing device comprising a segmental transfer carriage having plural sets of yarn-carrier ways located side by side in an arc of relatively large radius, a support having ways on which said carriage is adapted to be shifted back and forth in said arc to move the respective sets of ways into and out of registration with said stationary ways, the mounting for the transfer carriage being at its side remote from the center about which it is movable, a segmental gear on the transfer carriage, and means for shifting said transfer carriage back and forth including a gear meshing with said segmental gear.

5. In a straight knitting machine, a yarn-changing device comprising a transfer carriage, a plurality of sets of yarn-carrier ways on the carriage spaced apart in an arc, the radius of which is greater than half of the overall arcuate length of said ways on the carriage, and means supporting the carriage so that it is movable in said arc for positioning the sets of yarn-carrier ways respectively at a working station.

6. In a straight knitting machine, a yarn-changing device comprising a segmental transfer carriage for carrying a plurality of yarn-carriers spaced apart in arcuate relation and mounted for movement in an arc coincident therewith, the radius of which arc is of such length that at either extreme position of the carriage the yarn of the uppermost yarn-carrier will not interfere with those below.

7. In a straight knitting machine, in combination with the stationary ways, of a yarn-changing device having a segmental transfer carriage equipped with plural sets of yarn-

carrier ways located side by side in an arc of relatively large radius and adapted to be shifted back and forth in said arc to move the respective sets of ways into and out of registration with said stationary ways, a segmental gear on said transfer carriage, a pair of concentric gears of relatively large and small diameter, respectively, the larger of which meshes with said segmental gear, a translating bar having a rack meshing with the smaller gear, and a control mechanism for imparting comparatively short movement to said translating bar for shifting the yarn-carrier ways into and out of operative position.

8. In a straight knitting machine, in combination with the stationary ways, of a yarn-changing device having ways for plural yarn-carriers each adapted to be moved into and out of registration with the stationary ways, a wheel adapted to be continuously rotated and having on one side a single track, a portion of which is in the form of a switch pivoted on an axis parallel with the axis of rotation of the wheel and adapted to be shifted outwardly and inwardly from a neutral position in registration with the track proper and leaving in either shifted position a gap through the track, a translating bar connected with the yarn-changing device and equipped with a plurality of rollers in spaced relation each indicative of ways for a single yarn-carrier, said translating bar being so disposed that any one of its rollers may ride on the periphery of the track, and said switch being adapted to engage a roller either at the outer or inner side of the track and move it through the gap for shifting the translating bar in either direction.

9. In a straight knitting machine, the combination of a yarn-changing device, a gear wheel adapted to be continuously rotated and having a single track, a portion of which is in the form of a switch pivoted on an axis parallel with its axis of rotation, whereby the switch is adapted to shift outwardly and inwardly from a neutral position in registration with the track proper, a translating bar radially disposed with respect to the wheel and connected with the yarn-changing device, and a plurality of rollers on said bar in spaced relation indicative of different positions of the yarn-changing device and adapted to be respectively brought into guiding contact with said track by the action of said switch.

10. In a straight knitting machine, the combination of a yarn-changing device, a gear wheel adapted to be continuously rotated and having a single track, a portion of which is in the form of a switch pivoted on an axis parallel with its axis of rotation, whereby the switch is adapted to shift outwardly and inwardly from a neutral posi-

- tion in registration with the track proper, a translating bar radially disposed with respect to the wheel and connected with the yarn-changing device, a plurality of rollers 5 on said bar in spaced relation indicative of different positions of the yarn-changing device and adapted to be respectively brought into guiding contact with said track by the action of said switch, and control mechanism 10 for shifting the switch outwardly to engage the roller on the periphery of the track and move it inwardly to shift said bar and for shifting the switch inwardly to engage the roller at the inner side of the track and move 15 it outwardly onto the periphery thereof to thereby shift the bar in the opposite direction, the control mechanism being adapted to effect successive movements of the translating bar in either direction.
11. In a knitting machine, the combination of a yarn-changing device, a translating bar for operating said device, a continuously revolving wheel, a single track on said wheel, said bar being radial with respect to 20 said wheel and having a series of rollers each of which when riding on said track is determinative of a different position of the yarn-changing device, a switch in the track pivoted on an axis parallel with the axis of 25 rotation of the wheel for shifting said rollers and the bar in step-by-step movements for successively advancing and retracting said bar and correspondingly shifting said device, and means for controlling the switch.
12. In a knitting machine, the combination of a yarn-changing device, a continuously revolving wheel, a single track on the wheel having a shiftable portion, a bar movable radially with respect to said wheel for 30 translating movement to the yarn-changing device and having a series of rollers adapted to be successively brought into operative position on the track and determinative of the positions of the respective yarn-carriers, said rollers being adapted to be respectively positioned on the track by the shifting action of the movable track portion.
13. In a knitting machine, the combination of a yarn-changing device, a translating bar for shifting said device, a rotary wheel having a guide for said bar and a switch for shifting it and consequently the 35 yarn-changing device, a switch control mechanism, and means adapted to be actuated by said control mechanism for shifting said switch without transmitting resistance from the switch action back to said mechanism.
14. In a knitting machine, the combination of a yarn-changing device having a transfer carriage adapted for carrying a plurality of yarn-carriers and to be shifted for moving the yarn-carriers respectively to a working station, a bar for translating 40 shifting movement to said carriage, a plurality of rollers on said bar, one for each yarn-carrier, a continuously revolving wheel having an annular track including a switch, said rollers being in co-operative relation to the track and adapted to be shifted by action 45 of the switch in step-by-step movements for shifting the transfer carriage, a movable cam for shifting the switch adapted to be held in a neutral position and to be shifted to opposite sides of said neutral position for moving the switch in opposite directions, a stationary cam portion for returning the switch to a neutral position before reaching the movable cam, and mechanism for controlling the position of said movable cam.
15. In a knitting machine, the combination set forth in claim 14, in which the last-mentioned means comprises a control device, means operative between said control device and said cam for moving the latter, and means for preventing pressure imposed on said movable cam by the switch action from being transmitted back to the control device.
16. In a straight knitting machine, the combination of a yarn-changing device, a wheel adapted to be continuously rotated and having on one side a single track, a switch in said track pivoted on the wheel on an axis parallel with its axis of rotation and adapted to be shifted outwardly and inwardly from a neutral position in registration with the track proper, a translating bar radially disposed with respect to the wheel and connected with the yarn-changing device and equipped with a plurality of rollers in spaced relation indicative of different positions of the yarn-changing device and adapted to be successively brought into guiding contact with said track by action 55 of said switch, a control device, and means actuated by said control device for shifting said switch outwardly or inwardly.
17. In a straight knitting machine, the combination of a yarn-changing device, a wheel adapted to be continuously rotated and having on one side a single track, a switch in said track pivoted on the wheel on an axis parallel with its axis of rotation and adapted to be shifted outwardly and inwardly from a neutral position in registration with the track proper, a translating bar radially disposed with respect to the wheel and connected with the yarn-changing device and equipped with a plurality of rollers in spaced relation indicative of different positions of the yarn-changing device and adapted to be successively brought into guiding contact with said track by action of 60 said switch, a control device, and means actuated by said control device for shifting said switch outwardly or inwardly without transmitting resistance from the shifting action of the switch back to the control device.
18. In a stationary knitting machine, the

- combination of a yarn-changing device, a wheel adapted to be continuously rotated and having at one side a track including a switch which is pivoted on an axis parallel 5 with the axis of rotation of the wheel and is adapted to be swung outwardly and inwardly to provide a gap in the track and to present outer and inner surfaces of the switch in positions to effect changes in the 10 yarn-changing device, and a translating bar disposed in radial relation to said wheel and equipped with a plurality of spaced rollers each indicative of a position of the yarn-changing device and adapted to ride one at 15 a time on the periphery of said track and to be shifted outwardly or inwardly with respect to said track surface by the action of said switch for changing the position of the 20 yarn-changing device.
19. In a straight knitting machine, the combination of a yarn-changing device, and mechanism for shifting said device comprising a wheel adapted to be continuously rotated and having a single track a portion of 25 which is in the form of a switch pivoted on an axis parallel with the axis of rotation of the wheel and adapted to be swung outwardly and inwardly to provide a gap in the track when so moved, a reciprocable 30 translating bar equipped with a series of rollers each indicative of an operative position of the yarn-changing device and adapted to ride one at a time on the periphery of said track, and means for shifting 35 said track outwardly or inwardly, said track being so shaped that in its outer position it will engage the roller on the periphery of the track and move it inwardly through said gap to thereby move the translating bar in one direction and in its inner position will 40 engage the roller at the inner side of the track and move it outwardly through said gap.
20. In a straight knitting machine, the combination of a yarn-changing device, and mechanism for shifting said device comprising a wheel adapted to be continuously rotated and having a single track a portion of 45 which is in the form of a switch pivoted on an axis parallel with the axis of rotation of the wheel and adapted to be swung outwardly and inwardly to provide a gap in the track when so moved, a reciprocable translating bar equipped with a series of rollers 50 each indicative of an operative position of the yarn-changing device and adapted to ride one at a time on the periphery of said track, means for shifting said track outwardly or inwardly, said track being so shaped that in its outer position it will 55 engage the roller on the periphery of the track and move it inwardly through said gap to thereby move the translating bar in one direction and in its inner position will 60 engage the roller at the inner side of the track and move it outwardly through said gap.
21. In a knitting machine, the combination of a yarn-changing device, a wheel adapted to be continuously rotated and equipped at one side with a track a portion of which is pivoted on an axis parallel with the axis of rotation of the wheel to provide a switch adapted to be swung outwardly and inwardly, the switch leaving a gap in the track when swung to either of said positions, means connected to said yarn-changing device having a roller for each position thereof, the operative position of the yarn-changing device being determined by the roller in position on the periphery of the track and adapted to be changed by shifting of the 70 switch which when moved outwardly engages said roller and moves it inwardly through the gap and when moved inwardly engages the roller at the inner side of the track and moves it outwardly through the 75 gap, whereby the single switch is adapted to successively move said means in either direction.
22. In a knitting machine, the combination of a yarn-changing device, a wheel 80 adapted to be continuously rotated and equipped at one side with a track a portion of which is pivoted on an axis parallel with the axis of rotation of the wheel to provide a switch adapted to be swung outwardly and inwardly, the switch leaving a gap in the track when swung to either of said positions, means connected to said yarn-changing device having a roller for each position thereof, the operative position of the yarn-changing device being determined by the roller in position on the periphery of the track and adapted to be changed by shifting of the 85 switch which when moved outwardly engages said roller and moves it inwardly through the gap and when moved inwardly engages the roller at the inner side of the track and moves it outwardly through the 90 gap, whereby the single switch is adapted to successively move said means in either direction.
23. In a knitting machine, the combination of a yarn-changing device, a wheel 95 adapted to be continuously rotated and equipped at one side with a track a portion of which is pivoted on an axis parallel with the axis of rotation of the wheel to provide a switch adapted to be swung outwardly and inwardly, the switch leaving a gap in the track when swung to either of said positions, means connected to said yarn-changing device having a roller for each position thereof, the operative position of the yarn-changing device being determined by the roller in position on the periphery of the track and adapted to be changed by shifting of the 100 switch which when moved outwardly engages said roller and moves it inwardly through the gap and when moved inwardly engages the roller at the inner side of the track and moves it outwardly through the 105 gap, whereby the single switch is adapted to successively move said means in either direction.
24. In a knitting machine, the combination of a yarn-changing device, a wheel 110 adapted to be continuously rotated and equipped at one side with a track a portion of which is pivoted on an axis parallel with the axis of rotation of the wheel to provide a switch adapted to be swung outwardly and inwardly, the switch leaving a gap in the track when swung to either of said positions, means connected to said yarn-changing device having a roller for each position thereof, the operative position of the yarn-changing device being determined by the roller in position on the periphery of the track and adapted to be changed by shifting of the 115 switch which when moved outwardly engages said roller and moves it inwardly through the gap and when moved inwardly engages the roller at the inner side of the track and moves it outwardly through the 120 gap, whereby the single switch is adapted to successively move said means in either direction, a shiftable cam for controlling the position of said switch, control mechanism for shifting said cam, the connection between said control mechanism and cam moving in the same plane as the cam movement, and stops against which said cam is adapted to abut in its operative position for resisting the impact from shifting the switch, whereby said impact is not transmitted to the control mechanism.
25. In a knitting machine, the combination of a yarn-changing device, a wheel 125 adapted to be continuously rotated and equipped at one side with a track a portion of which is pivoted on an axis parallel with the axis of rotation of the wheel to provide a switch adapted to be swung outwardly and inwardly, the switch leaving a gap in the track when swung to either of said positions, means connected to said yarn-changing device having a roller for each position thereof, the operative position of the yarn-changing device being determined by the roller in position on the periphery of the track and adapted to be changed by shifting of the 130 switch which when moved outwardly engages said roller and moves it inwardly through the gap and when moved inwardly engages the roller at the inner side of the track and moves it outwardly through the gap, whereby the single switch is adapted to successively move said means in either direction.

the axis of rotation of the wheel to provide a switch adapted to be swung outwardly and inwardly, the switch leaving a gap in the track when swung to either of said positions, 5 means connected to said yarn-changing device having a roller for each position thereof, the operative position of the yarn-changing device being determined by the roller in position on the periphery of the track and 10 adapted to be changed by shifting of the switch which when moved outwardly engages said roller and moves it inwardly through the gap and when moved inwardly engages the roller at the inner side of the 15 track and moves it outwardly through the gap, whereby the single switch is adapted to successively move said means in either direction, said switch having a projection, a stationary cam against which said projection is adapted to contact for returning the 20 switch to a neutral position after each rotation of the wheel, a cam movable to any of three positions, namely, a neutral, an outer and an inner position, respectively, and being interposed in the path of said projection 25 so as to receive it from said neutral position and to control the subsequent position of the switch.

WALTER F. ROLSTON.
